UNITED STATES PATENT OFFICE

2,365,789

POSTAL CARD

Gosbert Weinschenk, Chicago, Ill.

Application May 22, 1942, Serial No. 444,077

2 Claims. (Cl. 229—92.8)

This invention relates to improvements in postal cards. One object is to provide a postal card particularly adapted for typewriter use that is so formed that the address and message can be typewritten without removing the card from the typewriter and without turning the card over during the process.

A further object is to provide a postal card that may be typed from the extreme upper edge to the extreme lower edge without the card shifting from its original position while being typed, particularly while being typed along its lowermost edge.

With the foregoing and other objects in view the invention consists in the combination and arrangement of parts to be hereinafter fully described, pointed out in the claims and illustrated in the accompanying drawings which form a part of this patent, and in which—

Fig. 1 is a face view of a postal card designed according to the present invention and ready for insertion in a typewriter except that one corner of the card is turned down to show a mucilaged portion.

Fig. 2 is a face view of the card made in strip form, one corner of one portion of one card being shown turned down, one card being shown partly broken away.

Fig. 3 is a face view of a modified form of card made in strips, certain cards being shown broken away.

Fig. 4 is a fragmentary view of the card showing the use of a second sheet for making a carbon copy when desired.

Fig. 5 is a face view of a modified form of card provided with a second sheet for making a carbon copy, the card and sheet being shown unfolded, a portion of the second sheet being broken away.

Fig. 6 is a view similar to Fig. 5 but showing the opposite side of the card and second sheet and a greater portion of the second sheet being broken away.

Fig. 7 is a view in elevational perspective on a reduced scale of the card and second sheet folded.

Fig. 8 is a plan view of a modified form of card with second sheet, in unfolded position.

Fig. 9 is a face view of a modified form of card with second sheet in folded position, ready for insertion in a typewriter, and,

Fig. 10 is a face view of Fig. 9 after it has been typed and addressed and is ready to be stamped and mailed.

Like reference characters denote corresponding parts throughout the several views.

Referring now to Fig. 1 a single card is shown but this card may, if desired, be made in strips as shown in Figs. 2 and 3, a number of cards forming a strip; the cards may then be individually torn from the strip as they are to be typed, or one end of the strip may be inserted in the machine and the cards successively or otherwise typed and thereafter the strip removed and the cards torn apart. Fig. 4 is identical with Fig. 1 except that a paper sheet 20 is mucilaged to the topmost edge of the card to provide means for making a carbon copy.

The reference numeral 1 denotes the body of the card which is oblong in shape and may be of the conventional postal card size, it being formed with the top flap 2 separated from said body by the perforated line or lineal groove 3, said flap 2 being mucilaged upon its reverse side and formed upon its front face with the spaced lines 4, 5 upon which the address is to be typed. Separated from the body 1 by the line 7 grooved or perforated is the bottom flap 6. In use the card is inserted in the typewriter with the flap 2 foremost and as the face side of the flap comes into position, the name and address are typed upon the lines 4, 5; the card is now advanced until the upper edge of the body 1 is in position, then the message is typed in the usual manner and this message may occupy the space from and including the upper longitudinal edge to and including the lower longitudinal edge, the card being held in position by the typewriter guides or paper bail engaging the flap 6 while the lower portion of the card body is being typed.

This insures steadiness of the card body in the machine while the lower line or lines are being typed. Formerly the card would be unsteady in its position in the machine while the lower lines are being typed due to the fact that the card had passed almost completely beyond the typewriter guides. The present card is engaged by the paper guides or fingers, first along the ends of the flap 2, next along the ends of the body 1, and finally along the ends of the flap 6. When the card is finished it is removed from the machine, the flap 2 is folded down upon the reverse side of the body 1 so that the mucilage causes it to adhere thereto, and the flap 6 is torn off along the perforated or recessed line 7 and the card is ready to be stamped or mailed. When this card is made in strips the flap 6 of each card except the last one is mucilaged and printed with address lines 4, 5 exactly like flap 2 and it then

becomes the top flap of the card body immediately below it.

Referring now to Fig. 2 the card is shown as made in strip form. The body 1 is provided with the flap 2 and with the "combination" flap 10 that is formed with address lines 4, 5 but that serves as a flap for the lower card body immediately thereafter and as an upper flap for the card body immediately therebelow, said flap 10 being mucilaged upon its reverse side and separated from the upper and lower bodies 1 by the perforated or grooved lines 13, 13a respectively; the final card body 1 of the strip being provided with a terminal flap 6 without address lines or mucilage.

Referring now to Fig. 3 a plurality of cards are shown forming a strip, the several card body portions 1 being separated from each other by perforated lines 16, the terminal body portions 1 carrying flaps 6a or 6 separated therefrom by perforated lines 16a. This strip is introduced into the machine with flap 6a foremost.

As the body portions 1 come into typing position the messages are typed thereupon and thereafter the strip is removed, the terminal flaps torn off and the card bodies torn apart along the lines 16 and then individually inserted and the addresses typed thereon. If these cards are made singly the body 1 carries flaps 6a, 6, respectively, along its top and lower edges.

Referring now to Figs. 5, 6 and 7 a single card with second sheet is shown, this card being known as an one-way speed card due to the fact that the address and message are written in one continuous operation and without removing the card from the machine. The reference numeral 30 denotes the cardboard or thick body portion of the card and 31 the thin second sheet portion, the portions 30, 31 being mucilaged together along the line 32, the message face of the card, proper, being shown in Fig. 5 and the address face in Fig. 6. The card is formed with a line of perforations 33 extending thereacross and spaced inwardly from the free edge 34 remote from the joined second sheet edge, the edge 34 in this form of card being the feeding edge or the edge to be introduced into the typewriter. The address face of the card is gummed at 35 from the line 32 inwardly almost one-third of the distance to the line 34. The second sheet 31 is formed with a transverse line of perforations 36 spaced inwardly from the junction line 32 a distance somewhat greater than the depth of the gummed surface 35. The remote free edge 34a of the second sheet corresponds to the free edge 34 of the card proper 30 and the length of the second sheet should be such that the edge 34a is spaced as far from the line of perforations 36 as is the edge 34 of the card proper. The second sheet is folded along the line of perforations 36 into the position shown in Fig. 7 with its edge 34a contiguous to the edge 34 of the card 30. A sheet of carbon paper is now placed between the card 30 and second sheet 31 and the card and second sheet introduced into the typewriter with the second sheet facing the operator and the card and second sheet edges 34, 34a foremost.

As the card and second sheet pass about the platen into typing position the message face of the card 30, shown in Fig. 5, will first be presented and the message will be typed thereon. After the message is completed the second sheet comes into typing position and the address is typed thereupon beginning at a point substantially $1\frac{1}{4}$ inches from the fold line 36, the space

between the line beginning the address being left clear for the postage stamp. The card and second sheet are now removed from the machine and the second sheet torn along the line of perforations 36. That portion of the second sheet between the line 36 and line 32 is now moistened and pressed upon the gummed portion 35 of the address face of the card 30 and the stamp applied. That portion of the card beyond the line 33 of perforations is now torn away and the card is ready to be mailed.

Referring now to Fig. 8 a card 40 of cardboard or like material is provided which is formed with a transverse line 41 of perforations spaced inwardly from its free edge 42 and with a gummed area 43 extending inwardly from its edge 44, as shown. Mucilaged to the edge 44 of the card is a second sheet 45 which does not overlap said edge, said second sheet being formed with a line of perforations 46 spaced from line 44 a distance substantially equal to the depth of the gummed area from said line. The second sheet is folded along the line 46 down upon the front or address side of the card but not yet adhered thereto. With the body portion of the second sheet facing the operator the card is inserted in the machine, that portion of the second sheet between the line 44 and line 46 entering first along the line 46 and thereafter the card and the balance 30 of the second sheet, with carbon paper interposed, moving about the platen. As the folded portion of the second sheet immediately above the line 44 comes into typing position the address is typed thereon and as the card comes into typing position the message is typed thereon.

When removed from the machine the second sheet is torn off along the line 46 and that flap portion between line 46 and line 44 is moistened and pressed into adhering position with the gummed area 43. The card 40 is torn along the line 41 and the card is ready to be stamped and mailed. That portion of the card between the free edge 42 and line 41 forms a flap to provide means for engagement by the paper clips or fingers of the typewriter to hold the card in position until the message is completely typed.

Referring now to Figs. 9 and 10 the card 50 is formed with a line of perforations 41a spaced inwardly from the free end 51. This card is formed with a gummed area 52 remote from its free edge 51 upon its address face and with a relatively narrow gummed area 53 across the message face and to said gummed area 53 one narrow edge 54 of the second sheet 55 is gummed, said second sheet extending outwardly beyond said edge 54 and then inwardly along the opposite face of the card, said second sheet being formed with a line of perforations 56 upon which the second sheet is folded. With the line 56 foremost, after the second sheet has been folded, the card and second sheet are introduced into the machine. As that portion of the second sheet between the edge 54 and the line of perforations 56 comes into typing position the address is typed thereon. As the message face of the card proper next comes into typing position the message is typed thereon and the card and second sheet then removed from the machine. The second sheet is now torn apart along the line of perforations 56 and the portion left beyond the edge 54 is folded down upon the gummed area of the address face of the card and adhered thereto. It will be noted that the remaining portion of the second sheet now completely

overlaps the upper edge of the card 50. The card is now torn along the line of perforations 41a and the card is ready to be stamped and mailed. The message side of the card as it then appears is shown in Fig. 10.

Manifestly, numeraus changes and modifications in the details of the embodiments of the invention disclosed will become apparent to those skilled in the art. It is intended that all such changes and modifications be comprehended within the scope of the invention which is to be limited only by the claims appended hereto.

What is claimed is:

1. In a postal card for typewriter use, a body portion having a line of perforations spaced inwardly from one edge, said body portion having a gummed area along its opposite edge upon one face and a narrow gummed area upon the opposite face, and a second sheet adhered to the narrow gummed area of said body, said second

20

sheet being formed with a line of perforations spaced from its gummed end, said second sheet being adapted to be torn away along said line of perforations and the adhered portion folded about the edge of said body portion and adhered to the large gummed area thereof.

2. In a postal card for typewriter use, a body portion having a line of perforations in spaced relation to one edge defining a portion to be torn away, the opposite edge of said body being gummed upon both sides, and a piece of relatively thin material adherent to one gummed edge of said body, said material being formed with a line of perforations to permit it to be folded thereupon and thereafter torn away thereupon, the adhering portion then being folded about the edge of said body and adhered to the second gummed area thereof.

GOSBERT WEINSCHENK.
